Primary Examiner—Robert M. Spear**Assistant Examiner**—Susan Bennett Hattan**(74) Attorney, Agent, or Firm**—Edward S. Wright(57) **CLAIM**

The ornamental design for an inflatable packing material, as shown and described.

DESCRIPTION

FIG. 1 is an isometric view of an inflatable packing material showing our new design;

FIG. 2 is a top plan view thereof, the bottom being a mirror image of the top;

FIG. 3 is an isometric view of the embodiment of FIG. 1, showing the inflatable packing material in an inflated condition;

FIG. 4 is a top plan view thereof, the bottom being a mirror image of the top;

FIG. 5 is a front elevational view thereof, the rear being a mirror image of the front; and,

FIG. 6 is a right side elevational view thereof, the left side being a mirror image of the right side.
